UNITED STATES PATENT OFFICE.

WALTER J. BAUMGARTNER, OF BROOKLYN, NEW YORK, ASSIGNOR TO DUPLEX ENGINE GOVERNOR COMPANY INC., OF BROOKLYN, NEW YORK, A CORPORATION OF NEW YORK.

INTERNAL-COMBUSTION ENGINE.

Application filed January 20, 1920. Serial No. 352,772.

To all whom it may concern:

Be it known that I, WALTER J. BAUMGARTNER, a citizen of the United States, residing in Brooklyn, in the county of Kings 5 and State of New York, have invented certain new and useful Improvements in Internal-Combustion Engines, of which the following is a specification.

I have invented an improvement relating 10 to internal combustion engines and comprising an operating connection for a governor designed to regulate and control the engine by limiting the speed of same.

An object of my invention is to provide 15 a device which is adapted to connect the governor of an internal combustion engine with a movable part of the engine capable of driving the governor, and which can be easily and conveniently installed without 20 material alteration of the engine or important parts thereof.

A further object of my invention is to provide a device which can be utilized to put such a governor into operative relation with an 25 internal combustion engine, and which is so constructed that it can cause the governor to be actuated from the cam shaft of the engine whether or not the latter is provided with an electrical generator of the type commonly 30 used for starting and lighting.

Other objects and advantages of my invention are set forth in the following specification, taken with the accompanying drawings, which present the best embodiment of 35 my invention now known to me. This disclosure, however, is explanatory only and I reserve the right to resort to changes not illustrated herein, but nevertheless within the scope and spirit of my invention as the 40 same is indicated by the general meanings of the terms in which the claims are expressed, and by variations of phrase specifying the novel features that the claims set forth.

On the drawings:—

Figure 1 is a side view of an internal combustion engine showing a governor with an operating connection according to my invention;

Figure 2 is a front view of what is shown 50 in Figure 1;

Figure 3 is a section of a support or housing for carrying some of the parts of my operating connection; the section being in a vertical plane running lengthwise of the engine, to which the housing is attached;

Figure 4 shows a front view of said housing;

Figure 5 is a view of this housing seen from the side to be attached to the engine;

Figure 6 presents this housing as seen 60 from the side opposite that presented in Figure 4;

Figure 7 shows this housing partly in section when employed upon an engine having 65 no outside generator for starting;

Figures 8 and 9 are respectively a side elevation, and a front elevation of a bracket for supporting such a generator; and

Figure 10 illustrates certain changes in 70 electrical wiring that may be necessary in the practice of my invention.

The same numerals identify the same parts throughout.

In the detailed description of the construction which is outlined in the figures 75 above mentioned, the numeral 1 is employed on Figures 1 and 2 to indicate an internal combustion engine for a motor vehicle, such as a commercial truck. This engine has an intake manifold 2 to which a 80 fuel supply conduit 3 leads from a carburetor 4. Between the carburetor and the intake manifold is a governor in a casing 5; this governor comprising a throttle valve controlled by centrifugal weights to diminish 85 the flow of fuel to the engine when the latter reaches a pre-determined speed and to shut off the gas entirely as soon as that speed is exceeded. The weights are caused to 90 revolve by a spindle passing through a tubular sleeve 6 and connected to the cam shaft of the engine 1, as will be described presently. The engine 1 also has a top or head 7, and an exhaust manifold and all other necessary parts, not appearing on the drawings 95 because they do not need to be shown herein. The carburetor 4 is of any approved type and the governor in the casing 5 is also well-known and does not need to be further described.

The engine 1 has a cam shaft indicated at 8 in Figure 2, extending lengthwise of the same; and it carries the usual half-time gear indicated at 9 thereon. This gear 9 is driven from the crank-shaft 10; and, as 105 usual in this type of engine, the front end of the shaft 9 actuates the timer mechanism, which is enclosed by the casing 11. The shaft 8, besides operating the cams for the valves of the engine and the timer mecha- 110

nism, is connected to rotate gearing in a support or housing 12. This housing is adapted to be readily attached to the engine by securing screws 13. It is held in place at one side of the engine, near the front end of the same, and on its rear face can be mounted an electrical generator 14 by means of screws 15. This generator is of the type commonly used for starting, lighting and other purposes and is held fast by the screws 15, which extend through the support 12 lengthwise of the engine and serve not only to hold the generator but also to secure to the front of the housing a plate 16. The outline of this plate is indicated in Figure 2 and it serves to close a portion of the front of the engine and to carry the timer casing 11. From the upper part of the support 12 there extends, in a rearward direction, the tubular sleeve 6, which houses the shaft to drive the governor in the casing 5. The plate 16, further, carries the oil-filler spout 17, through which lubricant for the interior of the engine 1 is admitted.

The support 12 is preferably made up in one piece by casting; although, of course, other methods of making it can be employed. Its lower portion 18 serves as a bracket for mounting the generator 14, and this bracket is therefore open in the front, at the rear and at one side, so that it can communicate with the inside of the engine 1. See Figures 3, 4, 5 and 6. On the interior of this bracket is a gear 19 which meshes with the gear 8 and is adapted to operate the generator 14 when such a generator is present. The support 12 also comprises an extension 20, on top of the bracket 18, containing gears 21, 22 and 23. The gear 21 meshes with the gear 19 and is mounted on the same shaft as the gear 22; this shaft being indicated by the numeral 24, and being mounted in bearings in the front and rear faces of the extension 20. The gear 22 meshes with gear 23 in the extension 20, and this gear 23 is carried by a shaft or spindle 25; said shaft 25 being carried in bearings in the front and rear faces of the extension and joined to the end 26 of a shaft in the tubular sleeve 6 for the governor in the casing 5. The side of extension 20 which is away from the engine may be open and provided with a removable cover 27 so as to give ready access to the gears above mentioned.

The support 12 with the gears therein is adapted for ready attachment to the engine in place of a bracket 28 which ordinarily mounts the generator 14. This bracket 28 is shown in Figures 8 and 9, and has the same shape as the bracket 18 without the extension 20. It is closed in front by the plate 16 and carries the generator 14 by having the latter made fast to its rear face by means of the bolts or screws 15, passed as before, through both the bracket and the

plate 16. It is held to the side of the engine by means of screws 13. Hence, to move this bracket, the screws 13 are first taken out and then the screws 15, so as to permit the separation of the bracket and the generator and the removal of the bracket from the engine. The bracket of the support 12 can then be substituted by attaching the lower part 18 to the engine in the same manner as when the bracket 28 is used; and the generator is mounted on the rear face of the bracket 18 of the support 12 by replacing the bolts or screws 15. When the engine is in operation the gear 8 turns the gear 9 to run the generator and the gear 19 acts through the gears above it to turn the shaft 25. In case there is no generator on the engine, the rear end of the bracket 18 will be closed by a plate 29 after receiving inside of it, a bearing-block 30, in which is mounted a spindle 31 carrying gear 19; and the governor can be then operated the same as when the generator is present.

When the generator is present, the cut-out box which is usually mounted thereon can be removed and mounted on the dash-board. This cut-out box is indicated at 32 in Figure 10. One terminal will be grounded as by the wire 32 and the wire ordinarily used running from the dash to the generator can be cut to make new connections.

My invention is primarily adapted for engines on trucks. The engine 1 is of a well-known design. To install my governor connection, one proceeds first to disunite one cable at the battery, if a generator is present. Then the hood on the carburetor side is opened and the generator dismounted by taking out the screws 15. If no generator is present, of course, the operation is simpler. The generator bracket 28 shown in Figures 8 and 9 is then dismounted by taking out the bolts 13. Then the support 12 is attached to the engine in the same position as the bracket 28, the screws 13 being replaced for this purpose. The generator 14 is then bolted to the rear face of the bracket 18 of the support 12 by the screws 15, passing as before through the plate 16 and the bracket 18. If there is no generator on the motor or engine, the plate 29 with the bearing block 30 therein is fastened to the rear face of the bracket 18. The cut-out box 32 is removed from the generator, fastened to the dash, and one terminal ground as above stated. Next the regular intake manifold, not shown, is separated from the engine 1, and the manifold 2 is substituted, the manifold having fastened thereto the casing 5, the elbow 3, and the carburetor 4; making a complete unit. The shaft of the governor is inserted into the end of the shaft 25 and into the sleeve 6, which is already attached to the support 12; and the manifold 2 is made fast.

The motor is then properly equipped with

a governor and operates as before, with or without the generator 14, and no other change in the structure of the engine is required to mount the governor thereon and thus secure proper control of the engine speed. The governor is adjacent the support 12 but a little above and to the rear of the generator 14, when arranged as shown in Figure 1, but obviously other relative positions may be selected, so long as the nature of the invention is not changed.

Of course the plate 29 and block 30 may be in one piece and such a construction in fact is preferable.

Having described my invention, what I believe to be new and desire to secure and protect by Letters Patent of the United States is:—

1. An attachable support or housing shaped to enable it to be secured to an engine, said housing comprising a bracket, said bracket being shaped to mount an electrical generator on the back thereof and to be covered by a plate in front, said support also being open at one side to communicate with the interior of the engine, an extension on the top of said bracket, and gears in said extension to operate a shaft extending therefrom.

2. A support adapted to be secured to an engine, the support having a bracket open at one side to communicate with the inside of the engine, the bracket being shaped

to support a generator at the back and to be covered by a plate in front, an extension on top of said bracket, gears in said extension to rotate a shaft extending therefrom, said extension having an opening, and a removable plate to close said opening.

3. An attachable support or housing shaped to enable it to be secured to an engine, said housing comprising a bracket, said bracket being open in front and back, and being shaped to mount an electrical generator on the back thereof and to be closed by a plate in front, said support also being open at one side to communicate with the interior of the engine, an extension on the top of said bracket, and gears in said extension to operate a shaft extending therefrom.

4. A support adapted to be secured to an engine, the support having a bracket open in front and back, and at one side to communicate with the inside of the engine, the bracket being shaped to support a generator at the back and to be closed by a plate in front, an extension on top of said bracket, gears in said extension to rotate a shaft extending therefrom, said extension having an opening, and a removable plate to close said opening.

In witness whereof, I have signed my name to this specification this 19th day of December, 1919.

WALTER J. BAUMGARTNER.
